UNITED STATES PATENT OFFICE

2,463,816

ELECTRICAL RESISTOR FOR LAMP SOCKETS

Louis Sokoloff, Chicago, Ill.

Application December 30, 1944, Serial No. 570,593

8 Claims. (Cl. 201—49)

1

My invention relates in general to electrical resistors. It relates more in particular to an electrical resistor in the general shape of a washer, insertable in the same socket with a lamp, and functioning to decrease the voltage to the lamp and thereby increase its life.

Frequently, it is desirable to provide special lamps, for example, for exit lights, to mark fire escapes, for pilot lights, and the like, where the brilliancy or light efficiency is not as important as lamp life and the assurance of the lamp's continued operation even though not serviced for long periods of time. Some higher rated lamps are produced. These lamps are too limited in rating and are not readily obtainable. Dealers do not ordinarily carry them in stock. Introduction of a resistance to decrease the voltage to the lamp will have the effect of greatly increasing the life of an ordinary stock size lamp when used in a position where long life is essential. A washer type electrical resistor of the type hereinbelow described, may be mounted in the same socket with a lamp to have the desired effect of increasing lamp life. Such a resistor may be loosely installed so that it will fall out when a lamp is removed; it may be removably secured in place or optionally locked in position. The resistance may be fixed or variable, and, preferably, means are provided to shunt out the resistance entirely, said shunting out means desirably being made available to an authorized person who may wish to use the full line voltage while the resistor is locked in the socket. As stated above, the washer resistor of the present invention is used in public places and is primarily a safety feature for pilot lights, exit lights, fire escape lights, etc. The lights or lamps thus used are of small size since light brilliancy is not important thereby creating little heat at the resistor and there is no problem of heat dissipation.

Detailed features and advantages of the invention will be understood by a consideration of the following description of the specific embodiment which is shown in the drawings.

In the drawings:

Fig. 1 is an elevational view, partly broken away and shown in vertical section, illustrating a theftproof lamp socket combination having disposed in the theftproof lamp socket thereof, a washer type electrical resistor having the novel features of my invention, a lamp being indicated as contained in the same socket;

Fig. 2 is a plan sectional view taken on the line 2—2 of Fig. 1;

2

Fig. 3 is an enlarged sectional view taken on the line 3—3 of Fig. 1, looking in the direction of the arrows;

Fig. 4 is an exploded view showing the main parts of the variable resistance;

Fig. 5 is a fragmentary view similar to Fig. 3 but illustrating the manner in which the variable resistance may be shunted out; and

Fig. 6 is a view showing a modified means for holding the resistor in a socket, this form otherwise being the same as in Figs. 1 to 5, inclusive.

While the resistor of my present invention may be used in any usual type of socket, I illustrate its use in connection with a theftproof lamp socket of the type shown in my prior Patent No. 2,194,329. In the form there shown, the washer type resistor, indicated generally by the reference character 10, is secured in a rotatable shell 11 of an adapter lock socket carrying a lamp 12. The shell 11 is rotatable on an adapter lock plug 13, adapted to be locked, if desired, in a socket 14, by means such as shown in my prior patent. The resistor 10 is placed between and engages both the center lamp contact and a center contact 16, thus placing a resistance between these two contacts by means which will later be described. Center contact 16 is held in position by a center rivet 17, which also has its head in electrical engagement with the center contact 18 of socket 14. The shell contact 11 is electrically connected to the shell contact of socket 14 through the fastening screws 19 in the manner described in my prior patent. A protective shell 21 is pivoted to the socket 13, also in the manner described in my prior patent, whereby to prevent removal of the lamp 12. Thus I provide one way in which the removal of the resistor 13 may be assured, even though it be of a type which is merely loosely disposed in the socket, as contrasted with being secured, or locked therein.

Further description of the washer type electrical resistor 10 will show that it may be used in various ways, and in any conventional type of socket, or even in a specially constructed socket, should there be any reason for so doing. In the form shown in Figs. 1 to 5, inclusive, there is a cup-like member 22 and a disk 23, the edge of the member 22 being peened or spun over the edge of the disk member to produce a closed housing. The annular portion 24 of the cup-like member is formed to provide large threads for engagement in the usual threads of a lamp socket. Slot-like impressions 26 are suitably formed to permit engagement by a suitable tool to screw resistor member 10 into position.

The housing is provided with a pair of pivoted curved dogs 27 functioning as selectively engaging locking members. As shown in Fig. 2, the dogs 27 are so arranged that when they are placed in one position and the disk-like or washer type resistor member 10 screwed into position, the said member cannot be withdrawn; but when placed in the opposite position the said resistor member can be withdrawn. The dogs 27 may have the same general construction and function as the members 41 of my prior patent and may thereby be movable between locking and non-locking positions for, respectively, permitting disengaging movement or preventing disengaging movement of the variable resistance member.

The variable resistance unit itself is held within the housing formed by the cup 22 and disk 23, and comprises a ring shaped disk 28 of mica or the like around which resistance wire 29 is helically wound. The outer and inner edges of the disk 28 may be serrated or notched in the manner shown to separate the resistance wire 29 from the edges thereof and thereby avoid possible contact with the metal comprising the housing. An insulating spacer 31 of mica or the like is placed on one side of the resistance carrying disk 28 and has a ring shaped center contact member 32 which is connected with one end of the resistance wire 29. The other end of the resistance wire 29 is fastened in position but is not electrically connected into the circuit except in so far as it may be contacted by an adjustable arm for controlling the amount of resistance in the lamp circuit. On the opposite side to the spacer 31 is a ring shaped spacer 33 having an integral radial projection 34. The spacer 33 is formed of insulating material such as mica or the like. Still another spacer 36 is provided and this spacer utilizes a center ring contact 37 and an integral wiper arm 38. The arm 38 is shaped so that a contact portion thereof will have a spring engagement with the convolutions of the wire 29 and is so related to the projection 34 that the latter may act as a stop to limit rotary movement of the sub-assembly comprising the spacer 36. The spacer 36 is provided with a notch 39 for the introduction of a tool such as a screw driver for adjusting the position of the arm 38.

The several parts comprising the resistor 10 are nested together in the same order in which the parts are pictured in Fig. 4, with the electrical connection made to the contact member 32, as previously described, and the parts are then secured together to produce a construction such as indicated in Figs. 1 and 3. The contact 32 makes a connection with the center contact member 16, as particularly seen in Fig. 3, and an electrical connection is thereby also made to one end of the resistance wire 29. The center contact of the usual rated voltage lamp 12 connects to the ring contact 37 and a connection is thereby made through the arm 38 to the opposite end of so much of the resistance wire 29 as is connected into the circuit as determined by the position of the arm 38. The amount of resistance can be predetermined by the use of indicating marks (not shown) on the relatively moving parts of the resistor 10 or in any other suitable manner such as by using a voltmeter in a test set up to meet conditions required in a particular installation.

With the identical construction of resistor shown in the drawings, some resistance will be introduced into the circuit, regardless of the adjustment of the arm 38 although the arm 38

can be adjusted to cause said resistance to be substantially negligible. An authorized person may wish to utilize the full voltage of the outlet without disturbing the adjustment of arm 38, and he may be permitted to do so by utilizing a special base 41 having a center contact 42 which is capable of extending through the relatively wide center opening ring contact 37 and directly into contact with the center contact 32 which is itself directly in contact with the center socket contact 16. This not only permits utilization of the full line voltage, but avoids the possibility of burning out the resistance wire 29 such as might occur if a power unit such as of a vacuum cleaner or the like were connected with the outlet socket.

I have previously stated that the resistor 10 may be formed merely to fit loosely in a socket, or to be fastened therein. The threads 24 will permit the resistor to be releasably secured in place, and by adjusting the dogs 27 to the position shown in Fig. 2, before the resistor is screwed into position, the said resistor may be locked in position.

In Fig. 6 I show a resistor which may be merely pushed into a socket, and held therein by a plurality of spring extensions 43 on the shell 22. These extensions 43 on the shell 22 may be a part thereof or may be secured thereon in any suitable way as by brazing or welding. The parts 30 of the resistor of Fig. 6 may otherwise be the same as in Figs. 1 to 5 and this fact is indicated by the use of the same reference characters. The dogs 27 are, of course, missing from Fig. 6, the spring extensions 43 being used instead.

As previously noted, the advantages of the combination of my invention are obtainable, particularly where light efficiency is not so much a factor as the life of a lamp which may be used. When a reasonable resistance is placed in a lamp 40 socket, the life of the lamp will be increased about ten times and the possibility of a lamp burning out is decreased also by a large ratio. The lock socket, if used, prevents removal of the resistor and also prevents changing of a lamp or the connection of a power unit such as a motor or the like, or even a higher wattage lamp, which would have the effect of burning out the resistance. If a lock socket is not used, the resistor 10 may still be locked in position if desired. I provide the features described in such a manner that an authorized person may utilize all or any portion of the resistance of the variable resistance unit, or cut out the resistance entirely if desired. A washer type resistor is advantageous 55 in locations where an extension resistor is undesirable. Interference is decreased because the resistance unit does not show on the outside of the socket and unauthorized persons are less apt to tamper with it.

While the resistor of my present invention has particular utility for the purpose described, it may be used in any situation where it is desired to deliver at the socket a lower voltage than provided in the line running to such socket.

What I claim as new and desire to protect by Letters Patent of the United States is:

1. A washer type electrical resistor having a contact on each side, a wire wound resistance electrically connected to said contacts, an enclosure holding said wire resistance and contacts together and enclosing the same, and spring means projecting slightly from the periphery of the enclosure so constructed and arranged that the resistor may be pushed into a lamp socket and be held therein by said spring means, said

resistor adapted to be installed in the same socket with a lamp whereby to decrease the voltage to said lamp and increase the life thereof.

2. A washer type electrical resistor having a contact on each side, a wire wound resistance electrically connected to said contacts, an enclosure holding said wire resistance and contacts together and enclosing the same, and exterior threads on said enclosure to permit its being screwed into a socket shell, said resistor adapted to be installed in the same socket with a lamp whereby to decrease the voltage to said lamp and increase the life thereof.

3. A washer type electrical resistor having a contact on one side thereof, a resistance wire helically wound and having one end connected to said contact, a turnable contact arm having a contact portion engaging resistance windings, a second contact connected to said arm, an enclosure holding said contacts and said resistance windings together, said resistor adapted to be held in the same socket with a lamp, and adapted to controllably reduce the voltage to said lamp, whereby to increase the life thereof.

4. A washer type electrical resistor having a contact on one side thereof, a helically wound resistance wire having one end connected to said contact, a turnable pointer having a contact portion engageable along the said windings, a second contact electrically connected to said pointer, means associated with said pointer for shunting out the resistance completely and an enclosure holding said contacts and resistance wire together, said resistor adapted to fit into the same socket with a lamp to reduce the voltage thereto and prolong life, or to deliver full voltage as desired.

5. A washer type electrical resistor having a contact on one side thereof, a helically wound resistance wire having one end connected to said contact, a turnable pointer having a contact portion engageable along the said windings, a second contact electrically connected to said pointer, means associated with said pointer for shunting out the resistance completely, an enclosure holding said contacts and resistance wire together, said resistor adapted to fit into the same socket with a lamp to reduce the voltage thereto and prolong life, or to deliver full voltage as desired, and means other than said shunting means for delivering full line voltage while said resistor is in a socket.

6. A washer type electrical resistor having selective means thereon movable between locking and non-locking positions for respective opposing and permitting removal from a socket prior to installing same, said resistor having a contact on each side thereof, a resistance wire electrically connected to said contacts and an enclosure hold-

ing said contacts and resistance wire together, said resistor adapted to fit in the same socket with a lamp, whereby to decrease the voltage delivered to said lamp, and increase the life thereof.

7. A resistor adapted to fit in the same socket with a lamp and functioning to decrease the voltage to the lamp and increase the life thereof, said resistor comprising a circular insulating disc having a contact secured at the center thereof, a disc of insulating material having a center opening, a resistance wire helically wound on said open center disc, a third insulating disc having a center contact with an inwardly extending radial arm, an enclosure clamping said discs together with the said open center disc between the other two, said enclosure having center openings to expose said contacts, one end of said resistance wire being secured to the first mentioned center contact, and said last mentioned center being rotatable to vary the resistance connected between the two center contacts, and means associated with said enclosure for supporting said resistor in a lamp socket.

8. A washer type electrical resistor having a contact on each side, a wire wound resistance electrically connected to said contacts, an enclosure holding said contacts and resistance wire together, one of said contacts centrally disposed whereby to align itself with a socket contact when inserted therein, the other of said contacts having a large central opening, whereby to permit insertion of a central contact as of a plug or the like entirely through said opening and make full voltage available in said socket or to insert a lamp using reduced voltage through the resistor and to increase the lamp life thereof.
